UNITED STATES PATENT OFFICE.

BENJAMIN F. MCKINLEY, OF CINCINNATI, OHIO.

HOT-AIR ENGINE.

SPECIFICATION forming part of Letters Patent No. 356,146, dated January 18, 1887.

Application filed April 19, 1886. Serial No. 199,434. (No model.)

To all whom it may concern:

Be it known that I, BENJAMIN F. MCKINLEY, a resident of Cincinnati, in the county of Hamilton and State of Ohio, have invented 5 certain new and useful Improvements in Hot-Air Engines, of which the following is a specification.

My invention relates to a hot-air engine, and is designed to secure greater efficiency 10 therein by increasing the cooling effect of a current of air upon the cooling-surface of the regenerating-chamber and upon the air contained within said chamber. It is especially adapted to be employed with a regenerating- 15 chamber containing a displacer operated in succession with a working-piston in a cylinder in communication with said chamber, substantially as shown in Letters Patent No. 206,597, granted me July 30, 1878. In engines 20 of this class employing a current of normal air to cool the regenerating-chamber upon its upper or cooling surfaces I have found that the radiant heat given off by these surfaces is not absorbed by the current of air, but is taken 25 up by the outer casing of the engine or outer wall of the air-flue, and a large portion of it is radiated back again to the surfaces of the regenerating-chamber, thus lessening the efficiency of the engine. I have found by experi- 30 ment that I can take up or intercept this dark radiant heat by charging the current of air with aqueous vapor generated at a low tem- 35 perature, and thus increase the efficiency of the engine by keeping the cooling-plates or other surfaces of the regenerating-chamber at a lower temperature, all of which will be set forth in the description and drawing, making a part of this specification.

The drawing represents a vertical central 40 section of a hot-air engine adapted to comprise my improvement.

A represents the upper or cooling disk of the regenerating-chamber; A', the lower or heating disk; B, the working-cylinder; D, the 45 working-piston; C, the pitman.

I is an outer cylindrical casing surrounding the cylinder, the regenerating-chamber, and the entire lower portion of the engine, and opening only at its top immediately around 50 the top of the working-cylinder. To the inside of the top part of the casing are attached

concentric pendent flanges f, which descend into the channels of the upper corrugated disk, A. The space between this casing and the cylinder and disk A forms an inlet-flue, through which a current of air is carried, and, flowing down within this flue to near the bottom of the engine, passes through openings d into the ash-pan, and thence through the fire, taking up heat and the products of combustion and 55 carrying them up against disk A', and thence through the space under said disk to flue S and uptake J to chimney, all substantially as set forth.

It is not essential that the cooling air-current shall be used to feed the fire; but when I so employ the air-current charged with vapor an additional benefit is received, for not only is the heat absorbed by the said current carried into and added to that of the combustion, but a still further benefit arises from the fact that as the air-current charged with vapor passes through the fire it becomes heated into steam, which, being disassociated into its component gases, furnishes material for more 75 perfect combustion. The more essential feature of my invention, however, is the use of the vapor to absorb the dark radiant heat given off by the upper disk, A, of the regenerating-chamber. The preferred method of 80 accomplishing this is to slowly introduce water by pipe g (or other means) into the trough h, formed by the corrugation of disk A, near cylinder B. The disk A being heated by the current of hot air forced over its under sur- 85 face by the displacer E, gives off vapor at a low temperature—say 100° to 212°—which is absorbed by the current of air entering the flue and carried along with it over the upper side of said disk A. The vapor takes up or 90 intercepts the dark radiant heat emanating from disk A, and prevents the outer case of the flue from receiving the heat and radiating it back again to the walls of the regenerating-chamber, and also assists the air in cooling 95 the same by contact, and thus cools the air within said chamber much more rapidly and effectually than when the cooling-current is not charged with vapor.

The water is properly regulated by means 100 of the cock i, so that only a thin stratum is resting on the disk A to give off the vapor

regularly and rapidly. The water can, however, be introduced onto other portions of the disk A, or the air-current might be charged with vapor outside of the entrance-flue *a* without affecting the essential feature of my invention. The essence of my invention is, one or more flues or air-passages so arranged with reference to the cooling-surface of a hot-air engine as to cause a current of air charged 10 with vapor to pass over and in close contact with said cooling-surfaces, and without reference to any special form of construction or to any particular method of producing the current of air or of charging the same with vapor.

15 I claim—

1. In a hot-air engine, the cooling portion of the regenerating-chamber, in combination with a flue, and cooled by passing through said flue a current of air charged with aqueous 20 vapor, substantially as specified.

2. A hot air engine employing a regenerating-chamber, in combination with a cooling-flue, and provided with a body of heated water for saturating a current of air passing 25 through said flue for cooling and taking up the radiant heat and cooling the regenerating-chamber, substantially as specified.

3. A hot-air engine having a regenerating-

chamber, one portion of which is cooled by a current of air charged with aqueous vapor by 30 coming in contact with the surfaces of said regenerating-chamber, substantially as specified.

4. A hot-air engine employing a regenerating-chamber, and having an air-cooling flue 35 and a body of water heated by said engine, by means of which the current of cooling air is saturated on its entrance into said flue, whereby the radiant heat of the regenerating-chamber is taken up by said aqueous vapor and 40 the surfaces cooled by the air contact, substantially as specified.

5. A hot-air engine employing a regenerating-chamber and one or more air-flues supplied by a current of normal air charged with 45 aqueous vapor upon its entrance into the air-flue, whereby the surfaces of the air-flue and regenerating-chamber are cooled, substantially as specified.

In testimony whereof I have hereunto set 5c my hand.

BENJAMIN F. McKINLEY.
